AUTOMOTIVE MUFFLER

Walter H. Powers, Jackson, Mich., assignor, by mesne assignments, to Walker Manufacturing Company, Racine, Wis., a corporation of Delaware

Filed Apr. 1, 1955, Ser. No. 498,639

7 Claims. (Cl. 181—54)

This invention relates to mufflers and, in particular, to mufflers for silencing the exhaust noise of automotive internal combustion engines.

It is the principal object of this invention to provide a muffler which is highly effective in silencing the exhaust noises of automobiles and yet may be readily manufactured at a low cost while being extremely sturdy and durable in construction.

The invention accomplishes this and other objects by means of a construction in which the various gas passages within the muffler casing are provided in a pair of stampings which are secured together. The stampings, commonly referred to as pancakes in the field, are secured to transverse partitions within the muffler casing. The inlet and outlet bushings are spot welded to the partitions, to the pancake, and to the end heads of the mufflers. As a result of this arrangement the various parts are rigidly interconnected and an extremely strong, durable construction resistant to leaks and blowouts is obtained.

In order to illustrate the principles of the invention a preferred embodiment thereof is shown in the accompanying drawings in which:

FIGURE 1 is a longitudinal section through a muffler embodying the invention;

FIG. 2 is an elevation taken at the inlet end of the muffler; and

FIG. 3 is a cross section taken along the line 3—3 of FIG. 1.

The muffler 1 has an oval sheet metal casing 3 of conventional construction, the parts therein also being formed of conventional materials, normally low carbon steel. The casing 3 is closed at the inlet end by a header 5 and at the outlet end by a header 7, both headers being interlocked with the metal of the casing 3 as shown by the joints 9. Within the volume of the casing 3 is an inlet partition 11 which extends transversely of the length of the muffler and which has an outer or peripheral flange that is spot welded to the casing 3 as shown at 15. There is another transverse partition 17 adjacent the outlet end of the muffler and this has a peripheral flange 19 that is spot welded at 21 to the casing 3. The inlet header 5 and the inlet partition 11 have aligned necks 23 and 25, respectively, formed by the flanges that extend toward the outside or outwardly of the muffler. Similarly, the outlet header 7 and the outlet partition 17 have aligned necks 27 and 29 formed by flanges extending toward the outlet end of the muffler casing 3. An inlet bushing 30 extends through the aligned necks 23 and 25 and is spot welded thereto as shown, respectively, by the reference numerals 31 and 33. In order to permit this assembly to be made the bushing 30 is expanded by a suitable expanding tool at 35 into tight contact with the neck 31 so that spot welding can occur after the header has been attached to the casing 3 and the internal parts assembled inside of the casing 3. The outlet bushing 36 is attached in a similar manner to the aligned necks 27 and 29, the bushing being spot welded at 37 to the neck 29 and expanded at 39 into contact with the neck 27 after all the parts have been assembled and then the flange 27 spot welded at 41 to the expanded part of the bushing 36.

Located between the two partitions 11 and 17 are a pair of complementary stampings 43 and 45 which define the gas passages through the volume of the casing 3. As will be clear from a consideration of FIGS. 1 and 3,

2

the stampings 43 and 45 have parallel longitudinally extending semicircular troughs 47, 49 and 51 pressed therein and when the stampings 43 and 45 are placed together, these troughs cooperate to define the gas passages 53, 55 and 57. There are flanges on the outside edges of the stampings 43 and 45 as shown at 54 and these are spot welded along with the webs 56 and 59 between the outer gas passages 53 and 57 and the inner gas passage 55. The stampings 43 and 45 are shaped so that the gas passages project a slight distance beyond the edges of the webs as will be seen most clearly in FIG. 1. The projecting portion of the gas passage 53 at the inlet end of the muffler fits into a neck or flange 60 in the partition 11 and is spot welded to it. Likewise, the projecting portion of the gas passage 57 at the inlet end fits in a flange 61 in the inlet partition 11 and is spot welded to it. The projecting end of the center gas passage 55 fits within the inlet bushing 30 and is spot welded to it as shown at 63. At the outlet end of the muffler the projecting portion of the gas passage 53 fits within the outlet bushing 36 and is spot welded to it as shown at 65. The projecting end of the gas passage 57 fits into a neck or outturned flange 67 in the outlet partition 17 and is spot welded to it as shown at 80. At the outlet end of the muffler the gas passage 55 is cut off as shown by the cutout 69. The inlet partition 11 has four small openings 71 formed therein and one larger opening 73 and these communicate the chamber 75 between the partitions 11 and 17 with the chamber 77 between the partition 11 and the inlet header 5. The partition 17 has no openings, that is, it is imperforate except for the openings provided by the necks 29 and 67.

It will be appreciated that the pancake construction, the partition, and the inlet and outlet bushings 30 and 36 can be preassembled as a spot welded subassembly and then inserted as a unit through an end of the casing 3 after which the partitions can be spot welded to the casing and headers 5 and 7 put in place and interlocked at 9. Since the bushings 30 and 36 are expanded at 35 and 39 into a tight (good spot weld) fit, the openings 23 and 27 can be substantially oversize, thus facilitating manufacturing and assembly by reducing the criticality of dimensions.

Turning now to the operation of the muffler, it will be seen that gas entering at the inlet nipple 30 will flow longitudinally through the gas passage 55 until it comes to the cross-over opening 69. Slots 79 or other openings formed in the troughs 49 provide transverse outlets for gas flowing through the passage 55. The gas flowing out of the openings 79 or out of the end of the passage 55 into the cross-over 69 enters the chamber 75 and since the partition 17 is imperforate the gas reverses its direction of flow and flows backwardly toward the inlet partition 11. The openings 71 and 73 in the partition 11 permit the gas in the chamber 75 to pass into the chamber 77 without substantial back pressure. The gas and sound waves in chamber 77 then can flow through the outlet passage 53 and through the outlet bushing 36 to the tail pipe of the automobile and thence to atmosphere. The outlet passage 53 has transverse slots or other suitable openings 79 formed in the troughs 47 and this permits by-pass flow of gas between the passage 53 and the chamber 75. Also communicating with the gas and sound waves in the chamber 77 is the imperforate gas passage 57 which empties into a tuning or resonator chamber 83 formed between the partition 17 and the outlet header 7. The gas passage 57 forms the only inlet and outlet to the chamber 83.

It will now be seen that the invention provides an economically constructed but durable and rugged muffler structure. While various modifications can be made without departing from the spirit and scope of the invention,

tion, the structure illustrated has been found to produce particularly satisfactory results intended in particular for use on six cylinder inline engines with fluid torque converters, the chambers 75 and 83 serving to control and eliminate the sustained heavy power note accompanying the use of fluid torque converters. The Chevrolet with Power Glide is a specific example of a car that could be muffled by means of the present construction.

I claim:

1. A muffler construction comprising a casing, inlet and outlet headers secured to the casing and closing the ends thereof, partitions spaced from each other and located within said casing and rigidly spot-welded thereto, an inlet bushing rigidly spot-welded to said inlet header and to the adjacent internal partition, an outlet bushing rigidly spot-welded to the outlet header and the adjacent inner partition, said bushings acting to transmit load on the headers to said partitions, and a pair of complementary stampings spot welded together and defining a plurality of gas passages connecting the inlet bushing to the outlet bushing, said stampings being spot welded to both said partitions and to the inlet and outlet bushings.

2. In a muffler construction, an oval shaped sheet metal casing, an inlet header interlocked with the casing to close one end thereof, an outlet header interlocked with the other end of the casing to close the end thereof, a transverse inlet partition within said casing and spot welded thereto, a transverse outlet partition within said casing and spot welded thereto and spaced longitudinally from said inlet partition, said inlet header and inlet partition having aligned openings with flanges extending outwardly thereof, said outlet header and partition also having aligned openings with flanges extending outwardly thereof, an inlet bushing seated in the flanged openings in said inlet header and inlet partition and spot welded to both said flanges, an outlet bushing in said openings in the outlet header and outlet partition and spot welded to both the flanges thereof, a pair of complementary sheet metal stampings contoured to fit the shape of said oval-shaped casing and spot welded together, said pair of stampings being provided with troughs interconnected by web portions that cooperate to define three parallel passages opening out of opposite ends of the assembly of stampings, two of said passages formed in said stampings projecting beyond the web portions of the stampings and being fitted in flanged openings in the inlet and outlet partitions and spot welded thereto, one of said passages constituting an inlet passage and fitting in said inlet bushing and being spot welded thereto, the other of said passages constituting an outlet passage and being fitted in said outlet bushing and spot welded thereto, said stampings being cut out so that the inlet passage terminates inwardly of said outlet partition and empties into a chamber defined by said casing between said inlet and outlet partitions and serving to empty inlet gas into said chamber, said inlet partition having relatively large openings therein to communicate said chamber with a chamber formed between the inlet header and the inlet partition, said outlet partition being imperforate except for said gas passage openings, the other of said gas passages serving to connect the chamber between the inlet partition and the inlet header with the chamber between the outlet header and the outlet partition.

3. In a muffler construction, a casing having an inlet and an outlet header, first and second transverse partitions inside of said casing and cooperating with said headers to define a first chamber between said inlet header and said first partition and a second chamber between said outlet header and said second partition, a pancake gas

passage construction extending between said partitions and supported at opposite ends by them, said pancake construction providing first, second, and third parallel gas passages, said first passage being directly connected to an inlet in said inlet header and emptying into a third chamber comprising the volume of said casing between said first and second partitions, said second passage being directly connected to an outlet in said outlet header and receiving gases from said first chamber, said first partition having openings connecting said third and said first chambers so that said volume comprises a flow passage for gas flowing from the first to the second passages, said second partition being imperforate except for an opening receiving said third gas passage, said third gas passage interconnecting said first and said second chambers.

4. The invention set forth in claim 3 wherein said pancake construction is provided with apertures that form louvers in the first and second gas passages, the third gas passage being imperforate.

5. The invention set forth in claim 3 wherein said pancake construction is formed so that said first passage terminates inwardly of the ends of the first and third passages and at an intermediate point in said third chamber.

6. In a muffler construction, a casing, a spot welded subassembly unit inside the casing comprising transverse partitions with inlet and outlet bushings spot welded thereto and a pancake gas passage construction extending between the partitions and spot welded at its ends thereto and to said bushings, headers closing the ends of the casing and interlocked therewith and having openings through which the bushings extend and outwardly extending flanges around said openings, said flanges being of greater diameter than all of the length of the respective bushing extending therethrough except that portion of the bushing registering therewith, said registering bushing portions being expanded into a tight fit with said flanges, and spot welds securing the flanges and registering portions together.

7. In a muffler construction having a casing with an inlet and an outlet, a pair of transverse partitions inside of said casing, a pancake gas passage construction extending between and secured at opposite ends to said partitions, said pancake comprising a pair of complementary sheet metal stampings spot welded together and defining a plurality of parallel and substantially co-extensive gas passages, one of said passages being directly connected at one end to said inlet, another of said passages being directly connected at one end to said outlet, said one ends of said respective passages being respectively at the opposite longitudinal ends thereof, and means providing for gas flow between the other ends of said gas passages comprising a large cutout portion in said pancake adjacent one partition and between said partitions, the other of said partitions having a large opening therein, the volume of the casing between said partitions and outside of said other partition comprising a flow passage connecting said other ends of said gas passages.
